MATTRESS AND MATTRESS COVER

Charles Lofman, Riverside, Ill., assignor to S. Karpen & Bros., Chicago, Ill., a corporation of West Virginia

Application January 2, 1932. Serial No. 584,487

2 Claims. (Cl. 5—356)

This invention relates particularly to mattresses and to the manufacture thereof; and the primary object is to provide for improved tufting of mattresses with the tufting cord or tape concealed 5 from view.

The invention is illustrated in the accompanying drawings, in which—

Figure 1 is a broken sectional view of a mattress tufted in accordance with my invention; Fig. 2, a 10 sectional view in elevation similar to Fig. 1, showing diagrammatically the method of tying; Fig. 3, a broken plan view of the mattress; Fig. 4, a broken perspective view of the tie member secured to one side of the mattress casing; Fig. 5, a 15 sectional view, the section being taken as indicated at line 5 of Fig. 4; Fig. 6, a perspective view of a tie member secured to an opposite side of the mattress casing; Fig. 7, a view of the tie member shown in Fig. 4 being tied to the tie member shown 20 in Fig. 6; and Fig. 8 shows the completion of the tying operation.

The invention is shown applied to a mattress having a filling which comprises a body of springs and layers of cotton or the like covering the 25 springs. However, the invention may be used in connection with mattresses having any suitable filling.

In the illustration given, A designates a filling comprising a spring structure A' and layers of 30 cotton or the like, A², over the spring structure, and B designates a casing for the mattress.

The spring structure A' shown is of the type in which coil springs are encased in fabric cells. The casing B comprises a top cover 10 and bottom 35 cover 11. The top and bottom covers, which cover the broad sides of the mattress, are connected with the boxing or border 13 by means of corner seams 14. If desired, the boxing 13 may be reinforced with quilting etc. 15.

40 My improved method of tufting mattresses comprises broadly the stitching of tie members to opposite inner sides of the mattress casing, drawing one of the tie members, by means of a needle, through the body of the mattress and tying it 45 to the other tie member.

In the illustration given, a tie member 16 is eyelet stitched to the top cover 10 in such a manner that a loop 17 is formed. As shown more clearly in Fig. 4, the free ends of the tie member are 50 brought together into overlapping relation and then secured by eyelet stitching to the cover 10. To the inner side of the bottom cover 11 at a point opposite to tie member 16, I prefer to secure a tie member 18 of the shape shown more clearly in 55 Fig. 6. The single strip of tape or cord is sewed,

by eyelet stitching, at about its middle point to the inner side of bottom 11.

In the stitching operation, I prefer to use an eyelet-stitching machine devised to accomplish the purpose and preferably a machine of 60 the type described in my co-pending application, Serial No. 525,750. While it is unnecessary to describe the eyelet-stitching machine in the present application, it may be stated that each eyelet is formed by means of upper and lower thread- 65 carrying needles which have essentially an annular movement, as well as a reciprocating movement, while the stitching progresses. Thus, the eyelet stitching forms an annulus on the fabric and tie member, as will be understood more 70 clearly from Fig. 5.

The tufting is accomplished, as illustrated more clearly in Figs. 2, 7 and 8, by thrusting a long needle 19 provided at its point with an eye through which a portion of the loop 17 is passed, through 75 the filling or body of the mattress, while the mattress is under compression, passing the needle point through the two legs of tie member 18, withdrawing the needle to free loop 21 and then passing the ends 20 of tape 18 through the loop portion 21 of the member 16 which extends 80 through the tape strips 18. A pull exerted upon the tie member 16 forms a secure knot, as illustrated in Fig. 8.

In the tufting operation it is preferred to start 85 near the center of the mattress and to work each way, the mattress body being placed under compression along the line where the tufts are being made.

By my improved method, I dispense with metal 90 eyelets and employ stitched eyelets which may be formed economically upon the imperforated fabric, the selected points being simply marked in advance of the eyelet-stitching operation to insure a desired arrangement or pattern for the 95 tufting. At the same time, the cords or tape used in the tufting operation are wholly concealed. The tufted mattress is sturdy and uniform in contour.

The foregoing detailed description is given for 100 clearness of understanding only, and no unnecessary limitations should be understood therefrom, but the appended claims should be construed as broadly as permissible, in view of the prior art.

I claim:

1. In the process of mattress manufacture, the 105 steps which include securing a tie member in the form of a loop to the inner side of the mattress casing, securing a strip of tape to the inner side of the casing opposite said first-mentioned tie 110

member, forming a mattress body in said casing, tufting the mattress by steps which include thrusting a tufting needle carrying said first-mentioned tie member through said mattress body and also through said tape, and looping the loop-end of said first mentioned tie member which has passed through said tape about the end of said tape member.

2. In the process of mattress manufacture, the steps which include stitching a tie member in the form of a loop to the inner side of the mattress casing, stitching an intermediate portion of

a strip of tape to the inner side of the casing opposite said first-mentioned tie member, forming a mattress body in said casing, tufting the mattress by steps which include thrusting a tufting needle carrying said first-mentioned tie member through said mattress body and also through a free end portion of said tape, and looping the loop-end of said first-mentioned tie member which has passed through said end portion of said tape about the end of said tape member.
